UNITED STATES PATENT OFFICE.

JOSEPH KOMOROUS, OF CHICAGO, ILLINOIS, ASSIGNEE TO PARISIAN NOVELTY COMPANY, OF CHICAGO, ILLINOIS, A CORPORATION OF ILLINOIS.

SHEET-METAL CONTAINER.

1,158,935.

Specification of Letters Patent. Patented Nov. 2, 1915.

Application filed December 1, 1914. Serial No. 875,048.

To all whom it may concern:

Be it known that I, JOSEPH KOMOROUS, a citizen of the United States, residing at 153 West Twenty-second street, Chicago, Illinois, have invented a new and useful Improvement in Sheet-Metal Containers, of which the following is a specification.

My invention relates to sheet metal containers, and more particularly to containers of the class which are composed of celluloid covered cover-sections with a connecting band-section, as is usual in certain forms of pocket savings banks and toilet boxes or containers.

My object is to provide a novel and simple construction of cover-section for such containers which will be economical of manufacture, will produce a container of exceeding neat appearance, and particularly in the case of a savings bank, will be strong and durable and provide for greater exposure of the band-section, whereby the operation of opening the bank by one having a suitable device, may be expedited, and in the case of a toilet case, will provide in a snap-cover means for holding a mirror or other article on the inside of the cover.

Referring to the accompanying drawings, Figure 1 is a view in edge elevation of a savings bank constructed in accordance with my invention. Fig. 2 is a section taken at the line 2 on Fig. 1, and viewed in the direction of the arrow. Fig. 3 is an enlarged section taken at the line 3 on Fig. 2, and viewed in the direction of the arrow. Fig. 4 is an edge view of a toilet container constructed in accordance with my invention, the container shown being of the snap-cover variety, with the cover disassembled from the body of the container. Fig. 5 is a face view of the inside of the cover; and Fig. 6, a section taken at the line 6 on Fig. 5, and viewed in the direction of the arrow.

Referring to Figs. 1, 2 and 3, the pocket savings bank therein shown is of a type commonly provided involving upper and lower similar cover-sections 7, and a band-section 8 releasably connecting the cover-sections together. The band-section 8 is in the form of a split ring and is provided at its free ends with a coin slot 9, a band 10 having its ends overlapped, as shown in Fig. 2, lying, under its spring tension, against the inner side of the band 8 and containing openings 11 and 12 relatively partially off-

set and registering with the opening 9, to prevent accidental release of the coins from the container.

The cover-sections 7 which are adapted to interlock with the opposite edges of the band 8, each consist of the following parts,— a metal blank 13 of circular shape having a continuous flange 14 provided about its periphery, a covering 15 of celluloid, or any other suitable material, which extends over the entire outer surface of the blank 13 and the flange 14, and is turned inwardly against the inner surface of the flange 14, as represented in Fig. 3; and a collet 16 fitting in the celluloid covered blank and against the inner continuous free edge of the covering 15, as shown in Fig. 3. The flange 14 and the ring portion 17 of the collet 16 are so shaped, as shown, as to provide a continuous undercut surface on each cover-section which is engaged by the edge of the band-section 8, which latter is preferably inclined to parallel the portion 17 of the collet.

The feature of having the edges of the band-section 8 interlocked with undercut surfaces on cover-sections is a well known form of construction, and the assembling of the cover-sections with the band 8 will therefore be readily understood by those skilled in the art.

My improvement consists in the provision of the collet for holding the free edge of the celluloid in place with a portion of the collet extending toward the center of the cover beyond the ring-section 17 and at an angle thereto and connected therewith, the collet in the case of the bank illustrated, and, as I prefer to form it when used in connection with a bank, having a continuous plate-section which is circular in shape and carries the ring-section 17 at its peripheral edge. By thus constructing the collet the cover-sections may be made very strong with a minimum of metal, no metal parts of the cover-section will be exposed to view, and the maximum width of the band-section 8 will be exposed, whereby the operator may readily apply to the band-section 8, the wrench commonly provided for contracting the latter to permit of the removal of a cover-section of the bank. Furthermore, the provision of the collet insures the presentation to the edge of the band-section 8 a smooth surface of a predetermined diam.

eter whereby accurate interfitting of the cover-section with the band section 8 is insured.

In the construction illustrated in Figs. 4, 5 and 6 my improvement is shown as applied to a toilet-container, as for example, one designed to receive powder or used for any other purpose, in which the cylindrical side of the container is permanently united to the bottom thereof, and the cover-section is adapted to be readily applied to and removed therefrom. The cylindrical side-section of the container is represented at 18, the lower edge of this member being slightly outwardly deflected throughout the periphery of the member 18, as represented at 19, at which it interfits with the base portion 20 of the container. The base portion 20 is formed of the members 13 and 15, as explained of the construction illustrated in the preceding figures, and the out-turned edge 19 of the member 18 interlocks with the continuous undercut surface provided on the member 20. The cover-section of the container is represented at 21 and is of exactly the same construction as the cover-section 7 of the preceding figures, excepting that the collet 16, instead of extending continuously across the inner face of the blank 13, is centrally cut away and its inner edge deflected downwardly and inwardly, as represented at 22, to form a continuous flange adapted to retain a mirror, represented at 23, or any other suitable article, in place on the inside of the cover 21.

The upper edge of the ring-section 17 telescopes with the cover-section 21 and carries small nubs 24 which, by reason of the springiness of the parts, snap past the edges 40 of the cover-section 21 upon applying the latter to the body portion of the container, and serve to releasably hold the cover in place (Fig. 6).

What I claim as new and desire to secure 45 by Letters Patent is:—

1. A cover-section comprising a disk having a flange along its edge, covering material extending over a face of said disk and against said flange, and a collet telescoping 50 said flanged disk and fitting against the portion of said covering material which overlies said flange, said collet being formed of a band-section of reinforcing material open at its outer end and provided at its inner 55 end adjacent to the body of said disk with a portion of reinforcing material which extends within the confines of said band-section

tion and at an angle to the latter and lies against the inner face of said disk.

2. A cover-section comprising a disk having a flange along its edge, covering material extending over a face of said disk and over the outer face of said flange and against the inner face of the latter, and a collet telescoping said flanged disk and fitting against the portion of said covering material which overlies the inner face of said flange, said collet being formed of a band-section of reinforcing material open at its outer end and provided at its inner end adjacent to the body of said disk with a portion of reinforcing material which extends within the confines of said band-section and at an angle to the latter and lies against the inner face of said disk. 75

3. A cover-section comprising a disk having a flange along its edge, covering material extending over a face of said disk and against said flange, and a collet telescoping said flanged disk and fitting against the portion of said covering material which overlies said flange, said collet being formed of a band-section of reinforcing material open at its outer end and provided at its inner end adjacent to the body of said disk with a ring-section of reinforcing material which extends within the confines of said band-section and at an angle to the latter and lies against the inner face of said disk, the inner edge of said ring-section being flanged, for the purpose set forth. 80

4. A cover-section comprising a disk having a flange along its edge, covering material extending over a face of said disk and over the outer face of said flange and against the inner face of the latter, and a collet telescoping said flanged disk and fitting against the portion of said covering material which overlies the inner face of said flange, said collet being formed of a band-section of reinforcing material open at its outer end and provided at its inner end adjacent to the body of the disk with a ring-section of reinforcing material which extends within the confines of said band-section and at an angle to the latter and lies against the inner face of said disk, the inner edge of said ring-section being flanged, for the purpose set forth. 100

JOSEPH KOMOROUS.

In presence of—

LOUIS L. JOSEPH,
MAX JOSEPH.
